UNITED STATES PATENT OFFICE.

LEE B. JONES, OF EVANSVILLE, INDIANA, ASSIGNOR TO SUNBEAM ELECTRIC MANUFACTURING COMPANY, OF EVANSVILLE, INDIANA, A CORPORATION OF INDIANA.

DETACHABLE END FRAME FOR ENGINES

Application filed June 18, 1921, Serial No. 478,664. Renewed January 17, 1928.

My invention relates to end frames used on prime movers and it has particular relation to a frame which closes one side of an engine crank casing and at the same time serves a 5 number of special purposes which will hereinafter be set forth.

One object of my invention is to provide a frame for closing one side of an engine crank casing; and while I will hereinafter describe 10 the end frame as applied to a particular construction it will be understood that its use is not so limited. In fact, it may be employed in many other prime movers wherein it is 15 desired to obtain structural and operative characteristics analogous to those hereinafter described.

The timing mechanism has associated therewith, on the end frame, a make-and-break device which is operatively associated 20 with a spark coil which is mounted on the exterior of the frame.

A better understanding of my invention, as 25 well as other objects thereof, will be apparent by reference to the accompanying drawings; in which,

Fig. 1 is an elevational sectional view of the prime mover portion of the power plant described in the above identified co-pending application, the detachable end frame being 30 shown in operative relation with the remainder of the mechanism;

Fig. 2 is a perspective view of the end frame showing the interior face thereof; and,

Fig. 3 is an elevational view of the end of 35 the crank casing and illustrates the exterior face of the end frame.

Referring more particularly to the drawings, one end of the main assembly unit comprises a crank casing 10 in which is journaled a fly-wheel 11. A connecting rod 12 is attached to a piston 13, the latter reciprocating in a cylinder portion 14 of another assembly unit 15. Admission valves 16 are provided whereby fuel is admitted from a manifold 17 to a space 18 directly above, and in communication with, the cylinder 14. To the left of the space 18 is formed an ignition pocket 19 at the bottom of which is an exhaust port 20 adapted to be closed by an exhaust valve 21, the latter being reciprocated by a valve rod 22 which is so associated with a spring 23 that it is normally held in closed a position.

The connecting rod 12 is not joined to the fly-wheel 11 by the usual U-shaped crank but, 55 as shown, is pinned directly thereto at 24.

A detachable end frame comprises a main portion 25 which has formed integrally therewith, and on the interior thereof, a bracket 26 which is mounted approximately 60 in the center of the frame. The bracket and the main portion of the frame provide a mounting for lower and upper shafts 27 and 28, respectively, intermeshing gears 29 and 30, respectively, being mounted on said shaft. A 65 cap piece 31 fits over the gears 29 and 30 and thereupon is mounted a portion 32 of the make-and-break device, the shaft 28 projecting thereinto and having an interrupter 33 mounted on the end thereof. A breathing 70 device 31^a allows air to pass through said cap 31 whereby the oil in the bath at the bottom of the casing is drawn up and around the gears and satisfactorily lubricates the 75 same.

The shaft 28 also has mounted thereupon a cam 28^a which actuates a tappet rod 34 extending upwardly through the frame and being adapted for abutting contact with the rod 22. On the interior end of the shaft 27 is adjustably mounted a crank 35 which is provided with a forked end 36, the latter being adapted to fit over a pin or reduced portion 37 of the crank pin 24, whereby the 80 crank 35 is rotated. This causes the rotation 85 of the shaft 27, and of the intermeshing gears 28 and 30, which, in turn, effects the reciprocation of the rod 34 and the opening of the exhaust valve 21. It will be noted that the crank 35 is secured to the end of the shaft 90 27 by a set screw 38 and it may, therefore, have its angular relation with respect to said shaft varied by loosening said screw. If desired this angular relation can be adjusted from the outside. Moreover, the set screw 95 adjustment is only illustrative since any other equivalent adjusting and securing means can be employed. A spark coil 39 is mounted 100 on the exterior of the end frame.

From a consideration of the above described mechanism the operation thereof is more or less apparent. When it is desired to vary the relation between the opening of the exhaust valve and the position of the piston at said opening, the end frame may be readily 105 detached and the crank 35 adjusted with re-

spect to the shaft 27 whereupon any desired relation may be obtained.

The structure which I have heretofore described is especially advantageous in view of the machine in which I have found its use most pertinent, although, as I have above pointed out, it should not be understood that I am limiting the use of this structure to internal combustion engines of the type illustrated. Because of the manner in which the relation between the crank and the valve is timed extreme accuracy of alignment is not necessary. The yoke or forked end 36 which fits over the reduced portion 37 functions even though there may be some slight departure from specification and this is a matter of particular advantage when it is remembered that the device of the above character is widely used in country districts where machine shop facilities for accurate adjustment are not available. The structure which I have just described can be set up without reference to the usual limitations which are imposed by the ordinary positioning of a crank pin.

Again the advantage of the interchangeable feature of my structure is emphasized in this field. End plates may be substituted, one for the other, without knowledge of valve timing and, in fact, it is the usual practice, when service in regard to repairs is required, to send the end plate to properly time or adjust the parts. It is obvious that, because the plate can be sent by itself and this very important adjustment made, a great deal of time is saved and in addition the cost of repair is sharply decreased because of the low shipping cost.

While I have described but one embodiment of my invention, many modifications therein may occur to those skilled in the art and I desire, therefore, that same be limited only by the showing of the prior art and by the scope of the appended claims.

Having thus described my invention what I now claim as new and desire to secure by Letters Patent, is:

1. In an internal combustion engine, a crank case and means comprising a crank therein, an end frame for said case, a spark coil mounted on said frame, shafts journalled interiorly of said frame, a make-and-break element mounted on one of said shafts in operative relation with said coil, a valve stem actuated by the same shaft, means connecting another shaft with said crank, and gearing between said shafts.

2. In an internal combustion engine, a crank case and means comprising a crank and a connecting rod therein, an end frame for said case, a spark coil mounted on said frame, shafts journalled interiorly of said frame, a make-and-break element mounted on one of said shafts in operative relation with said coil, a valve stem actuated by the

same shaft, means connecting another shaft with said crank, gearing between said shafts, and means for varying the relative positions of said valve stem and said rod.

3. In an internal combustion engine, a crank case and means comprising a crank and a connecting rod therein, an end frame for said case, a spark coil mounted on said frame, a shaft journalled in said frame and having a make-and-break device mounted thereon in operative relation with said coil, a valve stem actuated by the same shaft, a gear wheel on said shaft, another gear wheel driving said first gear and mounted on another shaft, a crank connecting said last-named shaft to said rod, and means for varying the relative positions of said valve stem and said rod.

4. In an internal combustion engine, a crank case and means comprising a crank and a connecting rod therein, an end frame for said case, a spark coil mounted on said frame, a shaft journalled in said frame and having a make-and-break device mounted thereon in operative relation with said coil, a valve stem actuated by the same shaft, a gear wheel on said shaft, another gear wheel driving said first gear and mounted on another shaft, a crank connecting said last-named shaft to said rod, and means whereby said crank may be turned loosely about said second shaft for varying the relative positions of said valve stem and said rod.

5. In an internal combustion engine, a crank case and means comprising a crank and a connecting rod therein, an end frame for said case, a spark case mounted on said frame, a shaft journalled in said frame and having a make-and-break device mounted thereon in operative relation with said coil, a valve stem actuated by the same shaft, a gear wheel on said shaft, another gear wheel driving said first gear and mounted on another shaft, a crank connecting said last-named shaft to said rod, and means for varying the relative positions of said valve stem and said rod, the axes about which said second shaft and said main crank rotate being coincident.

6. In a prime mover, a crank case, a detachable end frame for the latter having a bracket cast integrally on the interior thereof, and shafts extending between the body of said frame and said bracket.

7. In a prime mover, a crank case, a detachable end frame for the latter having a bracket cast integrally on the interior thereof, shafts extending between the body of said frame and said bracket, cooperative gears positioned on said shafts exteriorly of said frame, and a cap piece covering said gears.

8. In a prime mover, a crank case, a detachable end frame for the latter having a bracket cast integrally on the interior thereof, shafts extending between the body of

said frame and said bracket, a coil mounted on said frame, an interruptor device associated with the latter, and a make-and-break device on one of said shafts cooperating with 5 said interruptor device.

9. In a prime mover, a crank case, a detachable end frame for the latter having a bracket cast integrally on the interior thereof, shafts extending between the body of said 10 frame and said bracket, cooperative gears positioned on said shafts exteriorly of said frame, a coil mounted on said frame, a cap piece covering said gears, an interruptor de-

vice mounted on said cap piece, and means on one of said shafts extending into and co- 15 operating with said interruptor device.

10. In a prime mover, a crank case and means comprising a connecting rod and crank therein, a detachable end frame for said case, valve actuating shafts in said end frame, and 20 a crank adjustably mounted on one of said shafts and having a forked end engaging a portion of said rod.

In witness whereof, I have hereunto subscribed my name.

LEE B. JONES.
